UNITED STATES PATENT OFFICE

WILLIAM E. HART, OF SAN JOSE, CALIFORNIA

LIQUID-FUEL-FEEDING DEVICE FOR MOTOR VEHICLES

Application filed June 9, 1928. Serial No. 284,098.

The invention generally relates to vacuum tanks which are designed for drawing liquid fuel from a lower level source of supply and feeding said fuel by gravity to a carburetor of an internal combustion engine, and primarily has for its object to provide a new and improved construction of such tank wherein is provided a receiving chamber and a discharging chamber advantageously co-operatively arranged and in which means is provided to admit a suitable amount of atmospheric communication into the tank to provide for smooth and uninterrupted discharge of the liquid fuel while effectively preventing discharge of liquid fuel or vapor from said receiving chamber to atmosphere.

Another object of the invention is to provide a novel arrangement of main and auxiliary tank portions partially telescoped and removably secured together to form the receiving and discharging chambers, and a novel self cleaning valve through which communication between said chambers is had at times.

Another object of the invention is to provide means for equalizing the air control above the liquid fuel in the receiving chamber.

A further object of the invention is to provide a novel means for delivering the liquid fuel to the receiving chamber in a manner serving to prevent clogging of the chamber's communicating valve.

Other objects will in part be obvious and in part be pointed out hereinafter.

To the attainment of the aforesaid objects and ends, the invention further resides in the novel details of construction, combination and arrangements of parts, all of which will be first fully described in the following detailed description, then be particularly pointed out in the appended claims, reference being had to the accompanying drawings, in which:—

Figure 1 is a central vertical section of the tank, the parts being shown in the suction effecting condition.

Figure 2 is a view similar to Figure 1, the parts being shown in the non-pumping posi-

tion, and a modified form of valve mounting bracket being disclosed.

Figure 3 is a plan view.

Figure 4 is a detail horizontal section taken on the line 4—4 of Figure 1. 55

Figure 5 is a detail horizontal section taken on the line 5—5 on Figure 2.

Figure 6 is a detail view of the float and the control valve which is actuated by its rise and fall. 60

In the practical development of the invention I provide a main tank 1 preferably of sheet metal which forms within its confines a receiving chamber 2. The tank 1 carries a flange 3 secured thereon as at 4 by sweating or soldering and which extends outwardly to be secured on the mounting flange 5 carried at the upper end of an auxiliary or lower tank 6. 65

The flanges 3 and 5 are secured together by screws 7 which pass through apertures in the flange 3 and into threaded taps in the flange 5, and a gasket 8 is interposed between the flanges to make the joint liquid tight. 70

The tank 1 is closed at its top by a cover plate 9 and the tank 6 has a closed bottom 10. 75

An air tube 11 is secured to the side wall of the tank 1 and extends from a point above the cap of the said tank down along one wall thereof and through the flange 3 into the liquid fuel discharging chamber formed in the tank 6, thus providing for atmospheric communication into the said discharge chamber at all times. The tank 6 is provided with a reinforce boss 12 at its bottom which is provided with a threaded bore to receive the nipple 13 by which connection may be made to the carburetor (not shown). 80

A liquid fuel delivery nozzle head 14 is fitted in one wall of the tank 1 and includes a threaded bore to receive the nipple 15 by which connection may be made with the supply tank (not shown). The head 14 includes a narrow discharge throat 16 positioned to deliver close to and against the inner wall of the tank so that the liquid fuel delivered therethrough will pass down the cylindrical wall of the tank by a rotary or swirling motion. 85

This means of delivering the liquid fuel into the tank serves to keep the liquid fuel in 100

the tank in motion so that any foreign matter suspended therein will not be allowed to settle and clog the valve for controlling the passage of liquid fuel from the receiving chamber to the discharging chamber and which will be described in detail hereinafter.

10 The top or cover 9 carries a control head 17 which has a threaded bore 18 in which a nipple 19 is mounted to facilitate connection with any suitable source of suction (not shown).

15 The head 17 is provided with a vertical control valve bore 20 and a horizontally disposed air chamber or relief bore 21. A plate 22 closes over the upper end of the bore 20 and is secured as at 23 to the head and includes an orifice 24 through which air is admitted into the said bore. A similar plate 25 is secured as at 26 to cover the horizontal bore 21 and this plate is likewise provided with an air admitting orifice 27.

20 A communicating passage 28 is provided between the bore 20 and the receiving chamber 2, the purpose for which will later be described.

25 A valve head 29 is vertically reciprocable in the bore 20 and is provided with a cross duct 30 which passes through the said valve horizontally and is connected by a vertical connecting duct 31 with the communicating passage 28 and through that passage with the liquid fuel receiving chamber of the tank 1.

30 A duct 32 communicates between the suction connection and the valve bore 20 and another duct 33 communicates between the bores 20 and 21. The duct 32 is arranged on a low level so that when the valve is in its lowermost position as illustrated in Figure 1 communication will be open between the suction line, duct 32, and through ducts 30, 31 and the passage 28 with the interior of the tank 1 or liquid fuel receiving chamber. When the valve is shifted to its other extreme as illustrated in Figure 2, the duct 33 will be brought into function to open communication between the bore 21 and the ducts 30 and 31 and the passage 28 with the said liquid fuel receiving chamber.

35 A piston 34 is freely reciprocable in the bore 21 and is normally held to the position illustrated in Figure 1 of the drawings by a coil spring 5.

40 The bottom of the tank 1 is open and as will be observed by reference to Figures 1 and 2 of the drawings, is partially telescoped into the tank 6 so that its open end is surrounded by the said tank 6. The lower end of the tank 1 is equipped with a seat ring 36 of non-rusting metal of heavier gage than the tank and on which a flat disk valve 37 normally seats to close communication between the liquid fuel receiving and discharging chambers.

45 The valve 37 has secured thereto a cone 38 through which the screw 39 passes, and the said screw has its non-threaded end 40 passed

50 of a supporting lever or arm 41 which is provided at 42 on a bracket 43. The bracket 43 is secured at 44 to the tank 1 in the tank 6 and may be provided with teat and socket connections 45 to prevent displacement on its single screw mounting.

55 A spring 46 is connected to the lever arm 42 and to the bracket and serves to normally hold the valve in the seated position illustrated in Figure 1, a suitable abutment heel 47 being provided on the bracket to limit the opening of the valve as indicated in Figure 2 of the drawings. It will be observed that slightly modified means for mounting the valve 37 are illustrated in Figures 1 and 2 respectively.

60 To automatically provide for shifting of the control valve 29 so that the suction connection will be automatically opened each time it is necessary to replenish the supply of liquid fuel in the tank and to likewise automatically cut off suction connection when the supply has been suitably replenished, I provide a float 48 adapted to rise and fall in the receiving chamber 2 according to the liquid 65 level therein.

65 The float 48 is provided with a central tube opening 49 to adapt the same to freely slide on the valve head shifter stem 50 which is connected at 51 to the valve head 29 and is provided with upper and lower fixed cushion spring abutments 52. The float is free to slide on the stem 50 between the limits of the springs 52 but when the float moves far enough in either direction to engage one of the springs, continued movement of the float in that direction will cause a lifting or lowering of the shifter rod which will serve to snap-shift the valve 29 either to the position illustrated in Figure 1 of the drawings or from that position to the position illustrated in Figure 2.

70 To provide for this snap-shift of the valve the stem 50 is connected at its lower end by a toggle link 53 with a bracket 54 which is secured as at 55 to the wall of the tank 1. A retractile spring 56 is connected as at 57 to the bracket 54 and as at 58 to the stem 50. Thus each time the stem is moved in one direction or another by the float as the centers of the link 53 and spring 56 pass the dead center or aligning position the spring will serve to snap-throw the stem the remaining distance providing for certain and quick actuation of the valve 29.

75 In operation, assuming the parts to be in the position illustrated in Figure 1 of the drawings the suction through the connection 19 will be effective through ducts 32, 30, 31 and passage 28 to draw liquid fuel from the supply tank through connections 15 and throat 16 into the receiving chamber 2. As the float 48 is caused to rise in the said chamber it will finally engage the upper spring 52 and move the stem 50 upwardly.

As the stem 50 moves upwardly the link 53 and spring 56 will be brought into alignment and continued movement of the stem will cause the said link and spring to pass the dead center when the pull of said spring will snap-shift the stem upwardly to quickly complete the shifting of the valve 29 from the position illustrated in Figure 1 to that illustrated in Figure 2.

10 It should be remembered that when the parts were in the position illustrated in Figure 1 atmospheric communication was open into the bore 21. When the valve 29 is shifted to the position illustrated in Figure 2 the suction communication is cut off and communication between the bore 21 and the chamber 2. This will serve to allow the trapped air at atmospheric pressure in the bore 21 to pass into the chamber 2 and relieve the partial 15 vacuum therein without opening the said chamber to atmospheric communication.

With the vacuum in the upper end of the chamber 2 thus relieved when the weight of the column of liquid in the tank 1 overcomes 20 the balance of the liquid in the discharging chamber, the valve 37 will automatically open as illustrated in Figure 2 of the drawings and allow liquid fuel to pass from the receiving chamber into the discharging chamber to replenish the supply therein.

By providing the simply constructed disk valve 37 and rotatably mounting the same, it is possible for the said valve to automatically 25 keep its seat clean and assure efficient operation. Also by reason of providing and mounting the peculiarly constructed delivery head 14, 16 so that the fuel is delivered into the tank by a swirling motion clogging of the valve by sediment is assured against. This 30 circular delivery of the liquid fuel also assures against interference with float action.

The disk valve 37 is drawn tight across the seat ring 36 while in suction action as illustrated in Figure 1. The spring 46 tends to 35 hold the disk valve 37 lightly in the seated position. However, this does not prevent the liquid fuel in the receiving chamber 2 from opening the disk valve 37, as at times it may be that the liquid fuel will drop below high 40 level and below the center of the chamber 2 before the float 48 has shifted the valve 29 from the position illustrated in Figure 2.

By providing the peculiar construction of tank it is possible to provide for proper drawing 45 of liquid fuel into and the delivery of the said fuel from the tank without providing atmosphere communication direct into the receiving chamber, thus overcoming problems of evaporation in the said chamber. By providing 50 the peculiarly constructed and arranged valve device and the spring-pressed free piston in the air relief bore means is provided to assure quick action of the control valve and quick drawing of the desired charge of air 55 under atmospheric pressure into the bore 21.

From the foregoing description, taken in connection with the accompanying drawings, it is thought that the novel details of construction, the manner of use and the advantages of my invention will be readily apparent to those skilled in the art to which it relates. 70

What I claim is:

1. A device of the character described comprising a tank having separate liquid fuel chambers therein, a valve to control communication between the chambers, means providing for the introduction of liquid fuel into the tank and including a float controlled vacuum valve and a liquid fuel delivery head to deliver the liquid fuel into the tank above 75 said first named valve and to one side of the float with a swirling motion to agitate the fuel in the tank and prevent clogging of the valve and means providing for the delivery 80 of the fuel out of the tank. 85

2. A device of the character described comprising a cylindrical tank having separate liquid fuel chambers therein, a valve to control communication between the chambers, means providing for the introduction of liquid fuel into the tank and including a liquid fuel delivery head to deliver liquid fuel into the tank, said head having an intake throat and a delivery throat disposed to deliver 90 against and in the direction of curvature of the side wall of the tank to set up a swirling motion in the liquid fuel in the tank and overcome tendencies of foreign particles to settle therein and clog said valve and means 95 providing for the delivery of the fuel out of the tank. 100

3. A device of the character described comprising a tank having a liquid fuel receiving chamber and a discharging chamber, the lower end of the receiving chamber projecting 105 into the discharging chamber and communicating therewith, means to connect the receiving chamber with a source of liquid fuel supply, means to deliver liquid fuel from the discharging chamber, a valve through which 110 the chambers communicate and adapted to open when the supply of liquid fuel in the discharging chamber needs replenishing, said receiving chamber being closed to direct communication with the atmosphere, said discharging chamber being open to direct communication with the atmosphere, means to 115

connect the receiving chamber with a source of suction to draw liquid fuel thereinto, means to open and close the suction source 120 communication accordingly as the level of liquid fuel in the receiving chamber falls below or rises to a predetermined level, and means located on the top of the tank and active each time the suction communication is 125 cut off to relieve the partial vacuum above the column of liquid fuel in the receiving chamber and permit the valve to open for the purpose described.

4. A device of the character described com-

prising a tank having a liquid fuel receiving chamber and a discharging chamber, means to connect the receiving chamber with a source of liquid fuel supply, means to deliver liquid fuel from the discharging chamber, a valve through which the chambers communicate and adapted to open when the supply of liquid fuel in the discharging chamber needs replenishing, said receiving chamber being closed to direct communication with the atmosphere, said discharging chamber being open to direct communication with the atmosphere, means to connect the receiving chamber with a source of suction to draw liquid fuel thereinto, means to open and close the suction source communication accordingly as the level of liquid fuel in the receiving chamber falls below or rises to a predetermined level, said tank having an air trapping chamber therein provided with an opening to atmosphere when the communication with the suction source is effective, means active with the closing off of the suction source communication to close said air trapping chamber atmosphere opening and to open communication between the air trapping chamber and the liquid fuel receiving chamber for the purpose described.

5. A device of the character described comprising a tank having a liquid fuel receiving chamber and a discharging chamber, means to connect the receiving chamber with a source of liquid fuel supply, means to deliver liquid fuel from the discharging chamber, a valve through which the chambers communicate and adapted to open when the supply of liquid fuel in the discharging chamber needs replenishing, said receiving chamber being closed to direct communication with the atmosphere, said discharging chamber being open to direct communication with the atmosphere, means to connect the receiving chamber with a source of suction to draw liquid fuel thereinto, means to open and close the suction source communication accordingly as the level of liquid fuel in the receiving chamber falls below or rises to a predetermined level, said tank having an air trapping chamber therein provided with an opening to atmosphere when the communication with the suction source is effective, means active with the closing off of the suction source communication to close said air trapping chamber atmosphere opening and to open communication between the air trapping chamber and the liquid fuel receiving chamber, and a spring-pressed free piston operable in said trapping chamber to aid the in-drawing of air into the said trapping chamber.

6. A device of the character described comprising a tank having a liquid fuel receiving chamber and a liquid fuel discharging chamber, a valve through which the chambers communicate and adapted to open

when the supply of liquid fuel in the discharging chamber needs replenishing, said receiving chamber being closed to direct communication with the atmosphere, said discharging chamber being open to direct communication with the atmosphere, a valve chamber communicating with the receiving chamber, a suction duct adapted to be connected to a source of suction, means to connect the receiving chamber to a source of liquid fuel supply, means to deliver liquid fuel from the discharging chamber, a member having an air trapping chamber therein, a relief duct communicating between the trapping chamber and the valve chamber, an atmospheric air duct leading into the valve chamber, a control valve operable in the valve chamber shiftable to one position to open suction communication between the suction source and the receiving chamber and between the trapping chamber and atmosphere and shiftable in another direction to close the suction communication and the atmospheric air communication to the trapping chamber and to open relief communication between the trapping chamber and the receiving chamber, and liquid fuel level controlled means to shift said control valve.

7. A device of the character described comprising a tank having a liquid fuel receiving chamber and a liquid fuel discharging chamber, a valve through which the chambers communicate and adapted to open when the supply of liquid fuel in the discharging chamber needs replenishing, said receiving chamber being closed to direct communication with the atmosphere, said discharging chamber being open to direct communication with the atmosphere, a valve chamber communicating with the receiving chamber, a suction duct adapted to be connected to a source of suction, means to connect the receiving chamber to a source of liquid fuel supply, means to deliver liquid fuel from the discharging chamber, a member having an air trapping chamber therein, a relief duct communicating between the trapping chamber and the valve chamber, an atmospheric air duct leading into the valve chamber, a control valve operable in the valve chamber shiftable to one position to open suction communication between the suction source and the receiving chamber and between the trapping chamber and atmosphere and shiftable in another direction to close the suction communication and the atmospheric air communication to the trapping chamber and to open relief communication between the trapping chamber and the receiving chamber, a spring-pressed free piston operable in the trapping chamber, and liquid fuel level controlled means to shift said control valve.

8. A device of the character described comprising a tank embracing a liquid fuel re-

ceiving chamber and a liquid fuel discharging chamber, means to connect the receiving chamber with a source of liquid fuel supply, means to connect the receiving chamber with a source of suction, means for storing up a supply of air to relieve suction in the receiving chamber at times without opening the chamber to direct communication with the atmosphere, fuel level actuated devices to alternately close and open the suction and relief communications respectively, a liquid fuel column weight actuated valve between the receiving and discharging chambers, said discharge chamber being open to atmosphere, and means to deliver liquid fuel from the discharge chamber.

9. A device of the character described comprising a main tank closed at its top and open at its bottom and embracing a liquid fuel receiving chamber, means to connect the receiving chamber with a source of liquid fuel supply, means to connect the receiving chamber with a source of suction, means for storing up a supply of air to relieve suction in the receiving chamber at times without opening the chamber to direct communication with the atmosphere, fuel level actuated devices to alternately close and open the suction and relief communications respectively, an auxiliary tank carried by and surrounding the lower end of the main tank and forming a liquid fuel discharging chamber, means to provide constant communication between the discharging chamber and atmosphere, a spring held disk valve closing over the open bottom of the main tank, and means to deliver liquid fuel from the discharging chamber.

10. A device of the character described comprising a main tank closed at its top and open at its bottom and embracing a liquid fuel receiving chamber, means to connect the receiving chamber with a source of liquid fuel supply, means to connect the receiving chamber with a source of suction, means for storing up a supply of air to relieve suction in the receiving chamber at times without opening the chamber to direct communication with the atmosphere, fuel level actuated devices to alternately close and open the suction and relief communications respectively, an auxiliary tank carried by and surrounding the lower end of the main tank and forming a liquid fuel discharging chamber, means to provide constant communication between the discharging chamber and atmosphere, a spring held disk valve closing over the open bottom of the main tank, means to limit the degree to which the disk valve may open, and means to deliver liquid fuel from the discharging chamber.

11. A device of the character described comprising a main tank closed at its top and open at its bottom and embracing a liquid fuel receiving chamber, means to connect the

receiving chamber with a source of liquid fuel supply, means to connect the receiving chamber with a source of suction, means for storing up a supply of air to relieve suction in the receiving chamber at times without opening the chamber to direct communication with the atmosphere, fuel level actuated devices to alternately close and open the suction and relief communications respectively, an auxiliary tank carried by and surrounding the lower end of the main tank and forming a liquid fuel discharging chamber, an outwardly extended flange carried by the main tank, a mounting flange carried by the auxiliary tank, means to secure the flanges together liquid tight, means to provide constant communication between the discharging chamber and atmosphere, a spring held disk valve closing over the open bottom of the main tank, and means to deliver liquid fuel from the discharging chamber.

12. A device of the character described comprising a main tank closed at its top and open at its bottom and embracing a liquid fuel receiving chamber, means to connect the receiving chamber with a source of liquid fuel supply, means to connect the receiving chamber with a source of suction, means for storing up a supply of air to relieve suction in the receiving chamber at times without opening the chamber to direct communication with the atmosphere, fuel level actuated devices to alternately close and open the suction and relief communications respectively, an auxiliary tank carried by and surrounding the lower end of the main tank and forming a liquid fuel discharging chamber, means to provide constant communication between the discharging chamber and atmosphere, a ring seat mounted on the main tank to surround and extend below the open bottom thereof, a spring held disk to seat on the ring seat, and means to deliver liquid fuel from the discharging chamber.

13. In vacuum fuel tanks, a fuel delivering reservoir, a fuel receiving reservoir having its lower end in communication with the interior of said delivering reservoir and being closed off at all times from direct communication with the surrounding atmosphere, a float controlled suction valve for the receiving reservoir, a fuel inlet duct to the receiving reservoir, and means, operable when said suction valve is open, for storing up a relief supply of air, and when said suction valve is closed, delivering it into said receiving reservoir.

14. In vacuum fuel tanks, a fuel receiving reservoir and a fuel delivering reservoir in communication with one another whereby liquid will flow from the receiving reservoir into the delivering reservoir, means to maintain direct communication between said delivering reservoir and the surrounding atmosphere at a point above the liquid levels in

- said reservoirs, means for maintaining a pre-determined minimum supply of fuel in both said reservoirs, said means comprising a fuel inlet duct to the receiving reservoir, a suction duct in communication with the receiving reservoir and an air storing-up device arranged for communication alternately with the surrounding atmosphere and with the receiving reservoir, and a float operated valve controlling the action of both said air storing device and said suction duct.
15. In vacuum fuel tanks, a fuel receiving reservoir and a fuel delivering reservoir in communication with one another whereby liquid will flow from the receiving reservoir into the delivering reservoir, means to maintain direct communication between said delivering reservoir and the surrounding atmosphere at a point above the liquid levels in said reservoirs, means for maintaining a pre-determined minimum supply of fuel in both said reservoirs, said means comprising a fuel inlet duct to the receiving reservoir, a suction duct in communication with the receiving reservoir and an air storing-up device arranged for communication alternately with the surrounding atmosphere and with the receiving reservoir, and a float actuated air suction valve controlling the communication
- 20 of said suction duct with said receiving reservoir, and means actuated in cooperation with said air suction valve to permit communication between said device and the surrounding atmosphere only when said suction duct is
- 25 open, and to open communication between said device and said receiving reservoir only when said suction duct is closed.
